WEATHER VANE

John W. Bennett, Old Greenwich, Conn.

Application April 19, 1955, Serial No. 35,567

Term of patent 14 years

(Cl. D52—9)

FIG. 1

FIG. 2

FIG. 3

Fig. 1 is a front elevation of a weather vane embodying my new design.

Fig. 2 is a plan view of the same; and

Fig. 3 is a side view thereof.

The characteristic features of the design reside in the portion shown in full lines.

I claim:

The ornamental design for a weather vane, substantially as shown and described.
